PLUG-IN AUTOMOTIVE BATTERY CHECK METER

Elbert K. Mackenzie, North Wales, Pa., assignor to
Electro-Mechanical Instrument Co., Inc., Perkasie, Pa.

Filed Nov. 15, 1971, Ser. No. 199,081

Term of patent 7 years

Int. Cl. D10—05

U.S. Cl. D26—1 Q

FIG. 1 is a front perspective view of a plug-in automotive battery check meter showing my new design;

FIG. 2 is a right side elevational view thereof, the left side being a mirror image thereto;

FIG. 3 is a front elevational view thereof;

FIG. 4 is a rear elevational view thereof.

I claim:

The ornamental design for a plug-in automotive battery check meter, substantially as shown and described.
